US00D806784S

(12) **United States Design Patent** (10) Patent No.: **US D806,784 S**
 Sugioka (45) Date of Patent: ** Jan. 2, 2018

(54) **ELECTRONIC CALCULATOR WITH
PRINTER**

(71) Applicant: **CASIO KEISANKI KABUSHIKI
KAISHA**, Tokyo (JP)

(72) Inventor: **Shinobu Sugioka**, Saitama (JP)

(73) Assignee: **Casio Keisanki Kabushiki Kaisha**,
Tokyo (JP)

(**) Term: **15 Years**

(21) Appl. No.: **29/562,331**

(22) Filed: **Apr. 25, 2016**

(51) LOC (11) Cl. **18-01**
U.S. Cl.

USPC **D18/7**; D18/2

(57) **CLAIM**

The ornamental design for an electronic calculator with
printer, as shown and described.

DESCRIPTION

FIG. 1 is a front, right side, bottom perspective view of an
electronic calculator with printer showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front, left side, top perspective view thereof; and,
FIG. 9 is another front, right side, bottom perspective view
thereof, showing a used state of this article.

1 Claim, 8 Drawing Sheets
